United States Patent Office

Des. 188,934
Patented Oct. 4, 1960

188,934

SEWER CLEANING MACHINE

Howard T. O'Brien, Park Ridge, Ill., assignor to O'Brien
Manufacturing Corporation, Chicago, Ill., a corpora-
tion of Illinois

Filed Apr. 7, 1958, Ser. No. 50,349

Term of patent 14 years

(Cl. D9—2)

FIG. 1.

Des. 188,934

PAGE 2

FIG. 2.

FIG. 3.

Fig. 1 is a side perspective view of the sewer cleaning machine embodying my new design;

Fig. 2 is a front elevational view thereof; and

Fig. 3 is a back view thereof.

The dominant features of my design reside in the portions of the sewer cleaning machine shown in full lines.

I claim:

The ornamental design for a sewer cleaning machine, as shown and described.
